TIME CONTROLLED SWITCH

Filed May 9, 1930

UNITED STATES PATENT OFFICE

EVERETT E. STONE, OF BROOKLINE, MASSACHUSETTS

TIME CONTROLLED SWITCH

Application filed May 9, 1930. Serial No. 451,001.

This invention relates to time controlled electric switches and has for an object to provide for a simple switch mechanism which can be readily attached to and be actuated by any of a very considerable number of makes of alarm clocks without making any alteration in the clock. A further object is to provide such a switch which can either make or break an electric circuit at any desired time.

For a more complete understanding of this invention, reference may be had to the accompanying drawings in which

Figure 1 is a perspective showing the rear portion of an alarm clock having the switch attached thereto.

Figure 2 is a perspective of an attaching bracket.

Figure 3 is a section on line 3—3 of Figure 5 showing the switch adjusted to close a circuit at a predetermined time.

Figure 4 is a view similar to Figure 3, but showing the switch adjusted to break the circuit at a predetermined time.

Figure 5 is a side elevation of the switch showing the clock in dotted lines.

Referring to the drawings, at 1 is shown an alarm clock having an alarm winding stem 2 and a clock setting stem 3 of the usual construction. The switch comprises a casing such as 4 having journaled therein a shaft 5 which may be coupled to the alarm winding stem as by means of a threaded coupling member 6 fixed to the shaft 5 as by a set screw 7, it being understood that the usual winding element which has threaded connection with the alarm winding is removed and the coupling 6 substituted therefor. The casing 4 is shown as provided with a pair of segmental contacts 9 and 10 spaced by an insulating portion 11. The shaft 5 has fixed thereon a switch arm 12, this arm as shown being provided with a hub portion 13 secured to an insulating sleeve 150 surrounding the shaft 5 as by means of a set screw 14, the sleeve 150 being secured to the shaft as by means of a pin 151. Bearing on the outer face of the hub portion 13 is a conductor strip 15 which is pressed thereagainst by a coil spring 16 sur-

rounding the shaft 5 and reacting against the inner face of the casing. This conductor strip 15 is secured to a terminal post 17 as by means of a screw 18, this terminal post 17 having a wire binding screw 19 to receive a wire 20 in the electric circuit to be controlled by the switch. The opposite terminal 21 for connection to the wire 22 is carried by a shaft 23 journaled in the casing and having fixed thereon a contact arm 24 which also may be engaged with either of the contacts 9 and 10 at will by rocking the shaft 23 as by turning the terminal post 21. The casing has adjustably fixed thereto a bracket member 30 shown detached in Figure 2. As shown best in this figure, this member is provided with a slot 31 and side flanges 32. The side flanges may engage on opposite sides of the casing 4 and the bracket may be adjustably secured to the casing as by means of a screw 33 passing through the slot 31 and threading into the switch casing. This bracket has a slotted foot 35 which may be engaged on opposite sides of the setting stem 3 of the alarm clock and clamped against the rear face 36 of the clock by screwing the knob 37 on the setting stem thereagainst. This slotted construction of two arms of the bracket 30 permits the switch to be secured to any of a considerable number of makes of alarm clocks where the spacing between the alarm stem and another stem, such as the clock setting stem, may vary. To the outer end of the shaft 5 is shown fixed a knob 40 by which it may be turned. Stops in the form of pins 41 are shown to limit the rocking motion of the arm 12 and other stops as at 42 may be employed to limit the rocking motion of the arm 24.

The alarm stem is preferably wound somewhat before the switch is applied and the knob 40 is turned in winding direction as far as permitted by the stop so that when the alarm rings the switch arm 12 will be thrown in the other direction as far as permitted by the other stop 41. Some clocks are arranged to wind in one direction and some in the reverse direction. The present construction, however, is adaptable to either

direction by suitably adjusting the arm 24. For example, assuming that the direction of rotation of the stem 2 when the alarm goes off is as shown by the arrow in Figure 3 and it is desired to close the switch when the alarm goes off, the switch arm 24 will then be turned into engagement with the switch contact 9 and the switch contact 12 will be turned into engagement with the contact 10 which motion also winds the alarm. It will be noted that before the alarm goes off, the switch arm 12 engages the contact 10 while the switch arm 24 engages the contact 9. The switch is therefore in open position. When the alarm goes off the switch arm 12 is moved in the direction of the arrow into engagement with the contact 9 as far as it is permitted by the stop pin 41. This action closes the switch. Supposing, on the other hand, that it is desired to open the switch at a designated time, the clock having the same direction of winding of the alarm stem as before. The position of the parts is then as shown in Figure 4. The arm 24 is turned to engage the contact 10 so that before the alarm goes off, the switch is closed through the arm 24, the contact 10 and the arm 12. When the alarm goes off the switch arm 12 is swung in the direction of the arrow out of engagement with the contact 10 which breaks the circuit and into engagement with the contact 9. Where the winding direction of the alarm stem is opposite to that shown, the setting of the switch arm 24 in the position shown at 3 will cause the switch to be opened when the alarm goes off, since the switch arm 12 will swing from engagement with the contact 9 into engagement with the contact 10, while when the arm 24 is set into engagement with the contact 10, as shown in Figure 4, the switch will be closed when the alarm goes off, the arm 12 being swung from engagement with the contact 9 into engagement with the contact 10.

An embodiment of this invention having thus been described, it should be evident to those skilled in the art that various changes and modifications might be made therein without departing from the spirit or scope of this invention as defined by the appended claims.

I claim:

1. In combination with an alarm clock having an alarm winding stem and another stem, a switch having a shaft attachable to said alarm winding stem, and a supporting element for said switch securable to said other stem.
2. In combination, an alarm having an alarm winding stem and a clock setting stem, a switch having a shaft attachable to said alarm winding stem, and a supporting element for said switch securable to said setting stem.

3. In combination with an alarm clock having an alarm winding stem and another stem having a knob thereon, a switch having a shaft attachable to said alarm winding stem, and a supporting element adjustably securable to said switch and having a slotted portion engageable with said other stem and adjustably secured by said knob.

4. The combination of an alarm clock having an alarm winding stem and another stem, of a switch having a casing, a shaft journaled in said casing, a coupling for securing said shaft to said winding stem in axial alignment therewith, means on said element for turning said shaft to thereby wind said stem, a pair of spaced contacts, an arm fixed to said shaft, and movable by turning of said shaft from one to the other of said contacts, stops for limiting the rocking of said shaft in opposite directions, an element fixed to said casing and securable to said other stem for supporting said casing non-rotatably, a second shaft in said casing, an arm on said second shaft movable on rocking of said second shaft from one to the other of said contacts, and a wire terminal in electrical connection with each of said arms.

In testimony whereof I have affixed my signature.

EVERETT E. STONE.
